Application March 15, 1945, Serial No. 582,952

10 Claims. (Cl. 202—36)

1

This invention relates to method and apparatus for handling solid material in gas-solid or vapor-solid contact processes. Such processes may involve gas-solid heat exchange, gas adsorption, gasiform reactions in presence of catalysts, gas-solid reactions, solid regeneration or solid treatment. Typical processes are those of the high temperature treatment of oil bearing shales for recovery of hydrocarbons and the catalytic cracking of petroleum gas oil for the production of gasoline. For example, in the treatment of oil bearing shales, it is well known that hydrocarbons may be vaporized and recovered therefrom by the heating of such shales to temperatures usually in excess of about 1000° F. Such processes may be operated at substantially atmospheric pressures or at pressures thereabove and generally involve vapors which are condensable at ordinary atmospheric conditions.

A convenient method for solid introduction to gas-solid contact zones is by means of a substantially compact elongated column of downwardly gravitating solid particles. This invention is specifically directed to certain improvements in this method of solid feed introduction. When such feed legs are used for solid introduction, small quantities of gasiform material from the reaction zone tend to escape upwardly through the solid feed leg. In order to prevent such reactant or contact gas escape, an inert seal vapor, such as steam, may be introduced into the lower section of the feed leg. Some of this steam makes its way upwardly through the feed leg and if the solid feed particles are at a relatively low temperature, such as atmospheric temperature, the steam will be condensed on the solid particles. This condensation of vapor may eventually cause clogging or bridging of the solid flow in the feed leg resulting in partial or complete stoppage of solid flow to the contacting zone.

It is a major object of this invention to provide a method and apparatus for introduction of a relatively low temperature supply of solid particles to a gas-solid or vapor-solid contacting zone.

A specific object of this invention is the provision of a method and apparatus for gravity feeding of particle form solid particles to a gas-solid contacting zone while preventing substantial escape of contacting gases and while preventing substantial vapor condensation on the feeding solid particles.

Another specific object of this invention is the provision of a method and apparatus for intro-

2

ducing oil-bearing shale particles into a high temperature shale treating zone.

These and other objects of this invention will become apparent from the following description of the invention.

Before proceeding with this description, certain terms used hereinbefore and hereinafter in describing the invention and in the claiming thereof will be defined. The terms "gas" or 10 "gasiform material" or "gasiform fluid" unless otherwise specifically modified to the contrary are intended to broadly cover material in the gaseous phase at the conditions involved irrespective of the normal phase of the material at normal 15 atmospheric conditions. The terms "vapor" or "vaporous material" are intended to mean material in the gaseous phase which would exist in the liquid phase under the temperature and pressure conditions of the feed solid at the entrance 20 of the solid feed conduit.

The terms "normally gaseous fluid" or "normally gaseous material" are intended to mean material in the gaseous phase which normally exists in the gaseous phase under the temperature 25 and pressure conditions of the feed solid at the entrance to the solid feed conduit.

The invention may be more readily understood by reference to the attached drawings of which Figure 1 is an elevational view, partially in section, of a preferred form of this invention and 30 Figure 2 is a similar view of a modified form of the invention. Both of these drawings are highly diagrammatic in form.

Turning now to Figure 1, we find a closed contacting vessel 10, which may take any suitable 35 form adapted for the particular gas solid contact operation involved. A gasiform material inlet 11 is connected into the lower section of the vessel and a gasiform material outlet 12 at the upper section thereof. Gas distributor members (not 40 shown) may be provided in association with inlet conduit 11 and these may take any of a number of forms well known to those skilled in the art. A solid material feed conduit 16 extends a considerable distance above the top 15 of vessel 10 and on 45 its lower end extends through top 15 and a short distance therebelow so as to provide gas disengaging space 30. The conduit 16 should be of sufficient length to insure flow of solid material therethrough and into the contacting vessel 10 50 against whatever pressure may exist therein. A pipe 18 with valve 19 thereon connects into the lower section of conduit 16, and a perforated, rounded plate 20 is provided over the open end of pipe 18 to prevent solid flow thereto while permitting gas flow therethrough. A number of

louvered openings 21 are provided at an intermediate level on conduit 16; these openings are so constructed as to permit withdrawal of gasiform material without substantial loss of solid particles. A manifold box 22 is fastened to the conduit 16 around the louvered section and a vapor outlet pipe 23 is connected into this manifold box. A drain pipe 24 may be provided on the bottom of the manifold box for periodical removal of any small quantity of entrained solid particles. A pipe 25 for gas inlet is connected into the conduit 16 at a level substantially above that of the louvered section and a perforated metal plate 26 is provided at its inlet to prevent solid flow into pipe 25.

In operation a substantially compact column of solid particles may be maintained in vessel 10 by proper control of its rate of withdrawal therefrom through conduit 13 and valve 14. The contacting or reactant gases are heated to the desired temperature in an outside apparatus (not shown) which may be of conventional construction and then admitted through conduit 11 and passed upwardly through the solid material in vessel 10. The gaseous products are then withdrawn through conduit 12 through which they pass to a suitable recovery system (not shown). If desired, gasiform material may be introduced through conduit 12 and withdrawn through conduit 11 to effect concurrent flow of solid and gaseous material through the vessel 10. The temperature and pressure conditions within the vessel 10 will vary depending upon the operation involved. Generally elevated temperatures substantially above atmospheric temperature and pressures from about atmospheric to about 50 pounds per square inch may be maintained. A bed of particle form solid feed material is maintained in hopper 17 and feed therefrom downwardly through the conduit 16. The size of such solid particles may vary depending upon the operation involved but will be generally of sizes within the range of about 0.01 to 1 inch solid particle diameter. Thus, for example, the average particle diameter may be of the order of 0.02 to 0.2 inch for hydrocarbon cracking catalysts, while for oil bearing shales the particle size may be generally larger.

An inert vapor, such as steam, is introduced into the feed conduit through pipe 18 and passes in part downwardly through conduit 16 and out with contact gases through conduit 12 and in part upwardly through the compact stream of solid particles in conduit 16 to be withdrawn through louvered openings 21 and outlet pipe 23. An inert normally gaseous fluid, such as flue gas, is introduced through pipe 25 into conduit 16 and this stream divides, part passing upwardly and out through the hopper 17 and part passing downwardly to be withdrawn through pipe 23 along with the seal vapor. The inert gas so introduced is heated in a suitable external apparatus (not shown) such as a conventional "line" burner and introduced into conduit 16 at such a temperature and rate as to heat the moving solid particles in that section of the conduit 16 above the louvered outlets 21, so that said solid particles, upon reaching the louvered section 21, are at a temperature above the condensation temperature of the seal vapor employed. The inert gas passing downwardly through the solid material from inlet pipe 25 further serves to substantially prevent flow of seal vapor upwardly into that section of the column above the louvered outlets 21 where the solid temperature is below the con-

densate temperature of the seal vapor. Thus the condensation of seal vapor upon the solid feed particles is substantially avoided and the difficulties arising from such condensation are eliminated.

As hereinabove stated, the height of the conduit 16 should be sufficient to provide a head of solid particle column therein sufficient to overcome the gaseous pressure within the vessel 10. The required height will obviously vary depending on the operation involved and especially upon the density and physical properties of the solid particles involved. For example, in the case of clay-type granular material of about 40 pounds per cubic foot apparent unpacked density a height of about four feet per pound of pressure to be overcome in vessel 10 has been found satisfactory. The required height will be greater for less dense materials and less for more dense materials. If the pressure at the seal vapor outlet conduit 23 is to be substantially atmospheric, then the height of conduit 16 up to that level should be sufficient to permit a head of solid material between that level and the vessel 10 somewhat greater than that required to overcome the differential in pressure between that in vessel 10 and atmospheric pressure. In order to permit maximum utilization of available column height, especially in those operations wherein the pressure in vessel 10 is substantial, it is desirable to control the gaseous pressure at the level of conduit 23 above atmospheric and preferably near that pressure which would exist at the level of conduit 23 if it were absent and the seal vapor were forced to flow upwardly through the entire conduit 16. Thus, for example, assuming a gaseous pressure in the vessel 10 of 5 pounds per square inch gauge and a solid clay-type material of 40 pounds per cubic foot density, supplied to hopper 17 at atmospheric pressure, in the absence of vapor withdrawal at louvers 21 the conduit 16 should be about 20 feet high to overcome the pressure within vessel 10; and in order to allow for fluctuations in pressure, the conduit should be about 25 to 30 feet in height. Now assuming the seal vapor inlet 18 to be about 1 foot above the lower end of conduit 16 and the seal vapor outlet 23 to be about 4 feet further up the conduit 16, the gaseous pressure at the level of outlet 23 should be controlled near about 4 pounds per square inch gauge or slightly thereabove. Thus a diaphragm valve 27 provided on outlet 23 would be regulated to control the vapor and normally gaseous fluid flow through conduit 23 such that the pressure within conduit 16 at this level is maintained within a narrow range of pressures, say $4\frac{1}{4}$ to $4\frac{1}{2}$ #/in.², which are about three-quarters of a pound per square inch below the pressure in vessel 10. The diaphragm valve 27 is so regulated by means of the differential pressure control instrument 28. Similarly another diaphragm valve 29 is provided on inert gas inlet pipe 25 to control through differential pressure controller 31 the pressure within conduit 16 at the level of pipe 25 slightly above that in the conduit 16 at the seal vapor withdrawal level. The purpose of this control is to insure downward passage through conduit 16 of at least part of the normally gaseous heating fluid introduced through pipe 25. Inasmuch as the length of conduit between the levels of inlet pipe 25 and outlet pipe 23 is lost for purposes of overcoming pressure in the vessel 10, it is desirable to limit the length of the column between these levels as low as is consistent with provision of the proper heating

of the solid material by the normally gaseous fluid. Since the heat transfer rates for direct contact of gases with solids are very high, generally the length of column between the levels of inlet pipe 25 and outlet pipe 23 need be no greater than about one to two feet. It should be understood, however, that while where solid feed material is introduced to contact zones operating under substantial pressures the use of differential pressure control mechanisms, such as outlined hereinabove, is exemplary of the preferred form of this invention, nevertheless the use of such mechanisms is generally unnecessary for relatively low pressure operations and may also be omitted for higher pressure operations, where the provision of additional feed conduit height is unobjectionable from a practical standpoint. The invention, therefore, is not to be construed as limited in all applications to the use of such pressure control mechanisms nor, when used, to the particular example given hereinabove.

Turning now to Figure 2, we find another form of the invention modified mainly with respect to the method for heating the solid particles in the upper section of the feed conduit. Like members in Figures 1 and 2 bear like numerals. In Figure 2, only the upper section of the contacting vessel 10 is shown and it will be noted that the upper section of this vessel is somewhat modified by provision of partition 32 and dependent solid material distributor pipes 33 and flanged top 34. The partition 32 and flanged top 34 provide a solid material distribution space 35 which may also serve as a seal section by provision of a seal vapor inlet pipe 36 having valve 37 thereon on the vessel top 34. Seal vapor may, if desired, be introduced through conduit 36, in which case part of the seal vapor enters the lower end of the solid material feed conduit 16 and passes upwardly through the solid material therein, thereby eliminating the necessity for seal vapor introduction directly into the conduit 16 at some level thereabove. On the other hand, if desired, seal vapor may be introduced directly into the conduit 16 through inlet conduit 38, manifold box 39 and louvered openings 40 provided on the lower section of conduit 16. The seal vapor is withdrawn through louvered openings 41 and 42 which are similar to those shown in Figure 1 except that a double row of such openings is provided to further limit solid particle entrainment. A jacket 43 having heating fluid inlet 44 and outlet 45 thereon is provided along a section of conduit 16 above the seal gas withdrawal level to provide for heating of the solid material by indirect heat transfer with a heat exchange fluid. Any suitable heat exchange fluid, such as superheated steam, molten alloys or molten salts may be circulated through the jacket 43 and through a suitable external heating and circulating system which may be of conventional design and is, consequently, not shown. Other suitable indirect heat transfer arrangements may be provided instead of the jacket arrangement shown, such as small tubes within the upper section of conduit 16. When the solid material is so heated by indirect heat transfer, it is desirable to maintain a slightly reduced pressure on the seal vapor outlet conduit 23 so as to prevent flow of seal vapor into the cooler solid material thereabove. This may be effected by the use of a jet condenser 46, as shown, or by other suitable and conventional vacuum creating apparatus. Alternately, if desired, a small amount of normally gaseous fluid may be injected into the column a short distance

above the seal vapor outlet level to prevent the rise of seal vapor into the solid material thereabove, while still employing indirect heat transfer means for heating the solid material to a temperature above the condensation temperature of the seal vapor. In such case the use of the jet condenser is unnecessary.

The hereinabove described invention has been found particularly useful in a process for recovery of hydrocarbons at elevated temperatures from oil-bearing shales. In this process superheated steam was introduced into the lower section of the solid feed conduit as a seal vapor to prevent the escape of hydrocarbons through the feed conduit. Shale particles ranging from 1 to 0.125 inch average diameter were introduced into the upper end of the feed conduit and utilizing the method and apparatus hereinabove described, uninterrupted continuous feed of shale to the treating zone was provided without the clogging and interruption of feed flow which ordinarily results due to steam condensation on the low temperature shale in the feed conduit.

It should be understood that the details of apparatus construction and operating conditions and the systems shown to which this invention may be applied are intended merely as exemplary and are in no way to be construed as limiting the scope of this invention except as it may be limited by the following claims.

I claim:

1. In a system comprising an elongated feed conduit extending upwardly from a confined contacting vessel for gravity feed of particle-form solid feed material into said vessel the improvement comprising, an inlet pipe connecting into said elongated feed conduit near its lower end for seal vapor introduction thereinto, a gas outlet communicating with the interior of said feed conduit at an intermediate level along its length, a gas inlet pipe connecting into said feed conduit a substantial distance above said outlet, a flow control valve on said last named pipe, a differential pressure control instrument connected operatively with said valve and communicated with said feed pipe at the levels of said outlet and of said last named inlet pipe, whereby said valve may be controlled in response to change in pressure differential between said outlet and said last named inlet pipe.
2. In a process wherein a particle form solid material of size within the range about 0.01-1 inch average diameter is continuously passed through a confined contacting zone wherein it is contacted at elevated temperatures and superatmospheric pressures with a gaseous fluid which should be maintained confined from the atmosphere, the method of introducing the solid feed material to said contacting zone from a supply zone maintained at a lower pressure than exists in said contacting zone which comprises, continuously flowing said particle-form solid material from said supply zone by gravity into said confined contacting zone as a substantially compact, confined, continuous, moving feed stream of particles extending upwardly from said contacting zone to said supply zone through a vertical distance sufficient to insure gravity feed into said contacting zone against said superatmospheric pressure existing therein, withdrawing the contacted gaseous fluid from said contacting zone without passage through any portion of said feed stream while maintaining said superatmospheric pressure in said contacting zone, introducing a seal vapor which is different from said

contacted gaseous fluid into the lower section of said feed stream to substantially prevent entry of any of said contacted fluid into said feed stream, withdrawing gaseous material from said feed stream at an intermediate level substantially above the lower end of said stream, controlling the gaseous pressure in said feed stream at said level of fluid withdrawal below the pressure in that portion of said contacting zone into which said stream flows, introducing a substantially inert normally gaseous heated fluid into said stream at a level above said level of fluid withdrawal, at a sufficient temperature and rate to heat said solid material from a temperature below the condensation temperature of said seal vapor to a temperature above the condensation temperature thereof, and controlling the gaseous pressure at said level of said normally gaseous heated fluid introduction into said stream above the pressure at said level of fluid withdrawal from said stream but below the pressure in said contacting zone.

3. The method of continuously conducting reactions above atmospheric pressure and at elevated temperatures involving gaseous hydrocarbon reactants in the presence of a moving particle form solid contact mass material of size within the range about 0.01 to 1 inch average diameter which comprises: passing said solid material as a substantially compact column of solid particles moving continuously downwardly through a reaction zone while contacting it with hydrocarbon reactant gases at superatmospheric pressure and at elevated temperatures suitable for effecting the reaction, withdrawing particle form solid material from the lower end of said zone, continuously flowing said solid material by gravity from a supply zone maintained at a pressure substantially below the pressure in said reaction zone into said reaction zone as a substantially continuous, compact, confined moving feed stream of said solid material extending upwardly without interruption from said reaction zone to said supply zone through a sufficient height to insure solid material gravitation into said reaction zone against the superatmospheric pressure existing therein, withdrawing said hydrocarbon reactant gases directly from said reaction zone without passage through any portion of said feed stream while maintaining said superatmospheric pressure in said reaction zone, introducing an inert seal vapor into the lower section of said feed stream to prevent escape of reactant vapors therethrough, withdrawing seal vapors from said feed stream at an intermediate level a substantial distance above the lower end of said stream, whereby the pressure in said stream at said intermediate level is maintained below that in said stream immediately thereabove and therebelow, thereby preventing upward flow of vapors pass said intermediate level to the upper section of said stream, introducing a normally gaseous inert fluid into said feed stream at a level substantially above said level of seal vapor withdrawal at a temperature and rate adjusted to heat said solid material from a temperature below the condensation of said seal vapor to a temperature above the condensation temperature thereof, and maintaining the gaseous pressure at said level of normally gaseous fluid introduction above that at said level of seal vapor withdrawal but below that at the level of seal vapor introduction.

4. In a process for recovery of hydrocarbons from oil shale particles of size within the range about 0.01-1 inch diameter by continuous treat-

ment in a confined treating zone at superatmospheric pressure and high temperatures sufficient to effect release of the hydrocarbons in gaseous form from said shale particles, the method of introducing the shale to said treating zone from a supply zone maintained at a lower pressure than the treating zone which comprises, continuously flowing said shale by gravity from said supply zone into said treating zone as a substantially

10 compact, confined, continuous moving stream of particles extending upwardly without interruption from said treating zone through a sufficient height to said supply zone to insure gravity feed into said confined treating zone against said superatmospheric pressure existing therein, withdrawing recovered vapors from said treating zone without passage through any portion of said compact stream while maintaining said superatmospheric pressure in said zone, introducing an inert seal fluid in gaseous phase into the lower section 20 of said feed stream to substantially prevent entry of recovered hydrocarbon vapors into said feed stream, introducing a substantially inert normally gaseous fluid into said feed stream at a level in the upper section thereof so as to maintain gaseous pressure at said level of introduction which is below that in the upper portion of said treating zone but above that in the portion of said feed stream immediately below said level 25 of introduction, said inert fluid being introduced at a temperature and rate controlled to effect heating of said shale from a temperature below the condensation temperature of said first named seal fluid to a temperature above the condensation temperature thereof, withdrawing gaseous material from said feed stream at an intermediate level between the levels of said seal fluid and said normally gaseous fluid introduction so as to maintain the pressure in said feed stream at 30 said level of withdrawal below that at said levels of said seal fluid and said normally gaseous fluid introduction.

5. Apparatus for conducting gasiphase reactions at pressures above atmospheric in the presence of a moving particle-form solid contact mass material which comprises: a reaction vessel adapted for passage therethrough of a particle-form solid material as a substantially compact column of downwardly moving solid particles, a gas inlet to said vessel and a gas outlet therefrom spaced apart from said inlet, an elongated vertical feed conduit for solids extending upwardly from the top of said vessel and means to supply solids to the upper end of said feed conduit, a gas inlet pipe connected to said feed conduit near its lower end so as to be in communication with the interior of said feed pipe, a plurality of louvred openings around said feed conduit at a level spaced a substantial distance above said gas inlet pipe, said louvred openings being adapted to permit passage of gas therethrough while preventing gravity flow of solid particles therethrough, a gas outlet manifold box 50 connected around said column at the level of said louvred openings, a gas outlet pipe connecting into said manifold box, an automatic flow control valve on said pipe and an actuating instrument therefore adapted to automatically control the pressure in said conduit at the level of said louvred openings within a fixed range which is above atmospheric and below the pressure within said reaction vessel, a gas inlet pipe connected into said feed conduit at a level intermediate its upper end and the level of said louvred openings, means to supply heated gas to said last

named inlet pipe, and an automatic flow control valve on said last named inlet pipe and an actuating instrument associated with said valve adapted to control the pressure within said feed conduit at the level of said last named inlet a fixed amount above the pressure at the level of said louvered openings.

6. In a process wherein a particle-form solid material of size within the range about 0.01-1 inch average diameter containing constituents which may be separated therefrom as vapors by heating is treated in a confined treating zone at superatmospheric pressure and at elevated temperatures sufficient to effect separation of said constituents as vapors from said solid material the method of introducing the solid feed material to said treating zone from a supply zone maintained at a lower pressure than the treating zone which comprises: continuously flowing said particle form solid feed material by gravity from said supply zone into said confined treating zone as a substantially compact, confined, continuous moving feed stream of particles extending upwardly without interruption from said treating zone through a sufficient height to insure gravity feed into said confined treating zone against said superatmospheric pressure existing therein, withdrawing recovered vapors from said treating zone without passage through any portion of said compact stream while maintaining said superatmospheric pressure in said zone, introducing a seal vapor which is different from said recovered vapors into the lower section of said feed stream to substantially prevent entry of any of said recovered vapors into said feed stream, withdrawing gaseous material from said feed stream at an intermediate level substantially above the lower end of said stream, controlling the gaseous pressure in said stream at said level of fluid withdrawal below the pressure in that portion of said treating zone into which said stream flows, introducing a substantially inert normally gaseous heated fluid into said stream at a level above said level of fluid withdrawal, at a sufficient temperature and rate to heat said solid material from a temperature below the condensation temperature of said seal vapor to a temperature above the condensation temperature thereof, and controlling the gaseous pressure at said level of said normally gaseous heated fluid introduction into said stream above the pressure at said level of fluid withdrawal from said stream but below the pressure in said treating zone.

7. Apparatus for conducting gas-solid contact operations at pressures above atmospheric in the presence of moving particle-form contact material which comprises: an upright reaction vessel closed on its ends and having an outlet conduit for solids withdrawal connected into its lower end and having a gas inlet and a gas outlet, a vertical solid material feed conduit extending upwardly from the upper section of said vessel to a supply hopper spaced a substantial vertical distance above said vessel, a gas inlet pipe connected into said conduit near but above its lower end, a valve associated with said inlet, a gas outlet communicating with the interior of said conduit at an intermediate level along its length, an outlet flow control valve associated with said outlet, an automatic differential pressure controller associated with said outlet flow control valve operatively connected to control the pressure in said feed conduit at the level of said outlet within a fixed range which is above atmospheric and below the pressure within said reaction vessel, a gas inlet

communicating with the inside of said conduit near its upper end, an inlet flow control valve associated with said inlet and an automatic differential pressure controller associated with said inlet flow control valve operatively connected to control the pressure in said feed conduit at the level of said last named inlet a fixed amount above the pressure in said feed conduit at the level of said outlet.

8. A continuous method for treating particle-form solid materials of size within the range about 0.01-1 inch average diameter containing constituents recoverable as vapors by continuous treatment at superatmospheric pressures and elevated temperatures suitable for effecting release of said recoverable material from the solid material in a confined treating zone which comprises, continuously flowing said solid material existing initially at a temperature below that at which said recoverable constituents are vaporized downwardly into said treating zone as a substantially compact confined continuous feed stream of moving particles extending upwardly from said treating zone through a sufficient vertical distance to a supply location maintained at a pressure substantially below the pressure in said treating zone to insure feed into said treating zone against the superatmospheric pressure therein by gravity alone, passing the solid material through said treating zone while subjecting it at superatmospheric pressure to elevated temperatures to drive off said recoverable constituents as vapors, withdrawing said vapors directly from said treating zone without passing them through any portion of said compact solid material feed stream while maintaining said superatmospheric pressure in said treating zone, introducing a seal vapor which is different from said recoverable vapors and which is substantially inert into the lower section of said feed stream to substantially prevent the entry of any of said recovered vapors into said feed stream, heating said solid material in said feed stream along an upper section of said feed stream from a temperature below the condensation temperature of said inert vapor to a temperature above said condensation temperature, withdrawing said seal vapor from said feed stream at an intermediate level between the level of said seal vapor introduction and said upper section of heating and maintaining the pressure at said intermediate level below the pressure at said level of seal vapor introduction and below the pressure along at least a portion of the section of said stream which is undergoing heating whereby upward vapor now from said intermediate level to the portion of the feed stream thereabove is prevented.

9. A continuous method for continuously subjecting particle-form solid materials of size within the range about 0.01-1 inch average diameter to contacting in a confined contacting zone at superatmospheric pressure and elevated temperatures substantially above the initial temperature of the solid material with a gaseous material which would undergo reaction with air if permitted to escape to the atmosphere at said elevated temperatures, which method comprises, continuously flowing said solid material existing initially at a low temperature level relative to that in said confined zone downwardly by gravity from a supply zone maintained at a pressure substantially below the pressure in said contacting zone into said contacting zone as a substantially compact, confined, continuous, moving feed stream of particles extending upwardly without

11

obstruction from said contacting zone through a sufficient vertical distance to said supply zone to insure feed into said contacting zone by gravity alone against said superatmospheric pressure existing therein, passing the solid material through said contacting zone while subjecting it to contact with gaseous material at superatmospheric pressure and an elevated temperature substantially above that of the solid material in said supply zone, withdrawing the gaseous material after contact with said solid material directly from said contacting zone without passing it through any portion of said feed stream while maintaining said superatmospheric pressure in said contacting zone, introducing a seal vapor which is different from said gaseous material and which is substantially inert into the lower section of said feed stream to substantially prevent entry of any of said gaseous material from the contacting zone into said feed stream, heating said solid material in said feed stream along an upper section of said stream from a temperature below the condensation temperature of said seal vapor to a temperature above said condensation temperature, withdrawing said seal vapor from said feed stream at an intermediate level between the level of said seal vapor introduction and said upper section of heating and maintaining the pressure at said intermediate level below the pressure at said level of seal vapor introduction and below the pressure along at least a portion of the section of said stream which is undergoing heating, whereby upward vapor flow from said intermediate level to the portion of the feed stream thereabove is prevented.

5 10 15

20 25 30 35

12

10. The method of claim 9 characterized by the fact that said solid material is heated in the upper section of said feed stream from a temperature below the condensation temperature of said seal vapor to a temperature above said condensation temperature by passing a heating fluid in indirect heat exchange relationship with the solid material along said upper section of said feed stream.
